(57) **CLAIM**

The ornamental design for a pharmaceutical packaging, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a pharmaceutical packaging in color;

FIG. 2 is a front view thereof;

FIG. 3 is a top view thereof;

FIG. 4 is a rear view thereof;

FIG. 5 is a bottom view thereof;

FIG. 6 is a left side view thereof;

FIG. 7 is a right side view thereof;

FIG. 8 is a perspective view of a pharmaceutical packaging in grayscale;

FIG. 9 is a front view thereof;

FIG. 10 is a top view thereof;

FIG. 11 is a rear view thereof;

FIG. 12 is a bottom view thereof;

FIG. 13 is a left view thereof; and,

FIG. 14 is a right view thereof.

1 Claim, 14 Drawing Sheets
